(57) **CLAIM**

The ornamental design for a bench vise as shown and described.

DESCRIPTION

FIG. 1 is a top perspective view of a bench vise showing my new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the drawings depict portion of the article that form no part of the claimed design.

The dash-dot-dot broken lines shown in the drawings depict the boundary of the claimed design and form no part of the claimed design.
